(57) **CLAIM**

The ornamental design for a cut-off valve, as shown and described.

DESCRIPTION

FIG. 1 is a bottom perspective view of a cut-off valve, showing our new design;

FIG. 2 is a top perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof; and,

FIG. 8 is a top view thereof.

The broken lines shown in FIGS. 1-8 are included for the purpose of illustrating environment and forms no part of the claimed design.
